FREDERICK A. HART, OF JERSEY CITY, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,223,871.

Specification of Letters Patent. Patented Apr. 24, 1917.

Application filed November 28, 1911. Serial No. 662,873.

To all whom it may concern:

Be it known that I, FREDERICK A. HART, a citizen of the United States, residing in Jersey City, in the county of Hudson and 5 State of New Jersey, have invented certain new and useful Improvements in Combined Type-Writing and Computing Machines, of which the following is a specification.

This invention relates to means for writing a clearance sign upon the work sheet in 10 a combined typewriting and computing machine, and particularly a machine of the class in which one element of the computing mechanism is connected to travel step-by-step with the letter-feeding carriage.

An object of the invention is to provide 15 simple, inexpensive and reliable mechanism in this type of machine, for enabling the operator to prove that the computing wheels have been turned to zero.

In carrying out the invention, there is 20 provided a key connected to a clearance type, and this key is locked against actuation until it is automatically released by 25 the rotation of all the wheels to their zero positions, whereupon said key may be manipulated to print the clearance type, which may consist of a star or a special letter or character, which is different from the other 30 types of the typewriting machine.

This lock and automatic release for the 35 clearance key is effective at all positions of the typewriter carriage, and in case the computing head is mounted on said carriage, at all adjustments of said computing head along the carriage.

There is provided upon the computing 40 head a tumbler in the form of a bar extending along all of the computing wheels, and normally riding upon their peripheries. Each computing wheel has in its periphery 45 a single depression, and when the depressions are in line, (that is, when the wheels stand at zero), said tumbler will drop into the depressions or notches, and thereby release the clearance key for actuation. To connect such tumbler with the clearance key, there is provided a bar extending along 50 the run of the carriage in position to be engaged and operated by said tumbler at any position in which the computing head may be placed.

Other features and advantages will hereinafter appear.

In the accompanying drawings, the improvement is shown, for convenience, as applied to a type of machine known as the "Remington", having attached thereto adding mechanism known as the "Wahl"; although the improvement may be applied to other styles of typewriting machines and computing mechanisms.

Figure 1 is a diagrammatic sectional elevation taken from front to rear about centrally of a machine of the type described, showing my improvements applied thereto.

Fig. 2 is a front elevation of the upper part of the machine.

Fig. 3 is a diagram illustrating the clearance mechanism as locked against actuation.

Fig. 4 is a perspective view, showing the relation of the computing notched wheels and the tumbler.

Alphabet and numeral keys 1 are connected to levers 2 to throw type bars 2^a (by 75 means of connections 2^b) against a platen 3, which is mounted upon a carriage 4 controlled by dogs 5 and escapement wheels 6; said dogs being controlled by a universal bar 7 actuated by the levers 2.

Upon a bar or rack 8, extending along the front of the carriage, is adjustably mounted a computing head 9, having dial wheels 10, operable by gears 11, 12, and master wheel 13, the latter having connections 14 to the 85 numeral type keys, as usual in the "Wahl" machine, so that when any numeral key is depressed, its type is printed, and the dial wheel 10 is turned to a corresponding extent.

Upon each dial wheel 10 there is provided (Fig. 4) a notch 15, which may be of concave form, and may bear one of the numerals of the dial wheel, as for instance the numeral "9", as illustrated. Into these notches there may fall a universal tumbler 16, which is mounted upon a pair of arms 17 extending forwardly from a rock shaft 18, which is journaled in the casing of the adding head 9; said arms lying outside of the casing.

There may extend downwardly from said rock shaft 18 a pair of arms 19, forming with cross bars 20 a frame; and one or more draw springs 21, connected between the computing head and the arms 19, may pull 105 said tumbler 16 down into the notches 15, when the wheels all stand at zero; that is, when their zeros are all visible through a

sight opening 22 in the computing head; said bar 16 being preferably just back of said sight opening, and working through an opening 23 in said casing.

- 5 Whenever any of said dial wheels 10 is out of zero position, as at Fig. 3, the universal tumbler 16 is elevated, and a latch 24 is drawn by a spring 25 beneath a hook 26 on a lever 27 which bears a key 28, and is 10 connected by connections 29, to a type bar 29 having a special clearance type 30 thereon.

It will be seen that said latch depends from a frame which comprises a long horizontal bar 31 and a pair of arms 32 on which it is carried; said frame being hinged at 33 to the framework; the latch 24 being in the form of a long arm extending down from one of the arms 32.

- 20 The lifting of the tumbler 16 against the tension of spring 21, throws forward the bar 20, and permits the bar 31 to rise under the tension of spring 25, so that the latch 24 is thrown forwardly to lock the key 28 against actuation. The parts remain in these positions during the subsequent operation of the computing mechanism, and until the wheels are all brought again to zero, whereupon the tumbler is permitted to drop 30 into the notches 15 under the tension of the spring or springs 21, and the bar 20 cams downwardly the bar 31, (the bottom surface of the former being inclined at 34 for this purpose), and the latch arm 24 is 35 swung rearwardly, thus releasing the key 28. This operation may occur at any point in the run of the typewriter carriage 4, or at any point to which the computing head 9 is adjusted along the rack 8 on said carriage; the usual dog 35 being provided for locking the computing head to the rack.

Before beginning the writing or computation of a column, the operator brings the wheels to zero in the usual manner, and 45 then strikes the key 28 to prove that the computing wheels did not show any number thereon at the time of the beginning of the computation. Other uses of the device will be apparent to those skilled in the art. 50 Variations may be resorted to within the scope of the invention, and portions of the improvements may be used without others.

Having thus described my invention, I claim:

- 55 1. The combination with a computing head and a master wheel, of a carriage to which said computing head is connected for step-by-step movements, a clearance type-key on the framework of the machine, and 60 means controlled by said computing head in various positions thereof for locking and releasing said clearance type-key.

2. The combination with a master wheel and a set of computing wheels, of a carriage 65 to which said computing wheels are connect-

ed, a bar extending along the run of said carriage, a clearance type-key upon the framework of the machine and controlled by said bar, and means for causing said wheels to operate through said bar to render said key effective or ineffective. 70

3. The combination with a master wheel and a set of computing wheels, of a carriage to which said computing wheels are connected, a bar extending along the run of the carriage, a type-operating clearance key upon the frame of the machine, a latch for locking said key, and means operating through said bar to enable said wheels to cause the latch to lock and release the key. 80

4. The combination with a master wheel and a set of computing wheels, of a carriage to which said computing wheels are connected, a bar extending along the run of the carriage, a type-operating clearance key upon the frame of the machine, a latch controlled by said bar for locking said key, a tumbler, said computing wheels being provided with notches into which said tumbler may fall when all the wheels stand at zero, and means to cause said tumbler to operate said bar at different positions of said carriage. 90

5. The combination with a letter-feeding typewriter carriage and a rack thereon, of a computing head adjustable along said rack and comprising a set of computing wheels, each of said wheels having a notch, a tumbler mounted upon said computing head and extending along said wheels, a spring to cause said tumbler to fall into the notches when the wheels all stand at zero, a bar extending parallel to the run of the carriage, said tumbler hinged upon said computing head and having a part to engage and operate said bar, an arm rigid with said bar and having a latch thereon, a type-operating clearance key having a hook, and a spring to move said latch to engage said hook. 100

6. The combination with computing mechanism, of printing means, a key for controlling the action of said printing means, locking means for said key, said computing mechanism having a traveling element, and controlling means for governing said locking means from said traveling element in all positions of the latter. 110

7. The combination with a traveling computing mechanism, of means for indicating a certain state of said computing mechanism, a lock for said means, and connections universal to any position of said traveling computing mechanism for controlling said lock from said computing mechanism. 120

8. The combination with a bank of keys, of type actions actuated by said keys, to enable a typewriting operation, computing mechanism having a traveling element, a special type action, a special key arranged 130

in juxtaposition to said bank of keys for actuating said special type action, and locking means individual to said special key and universal to all positions of said traveling element, so that said special key may be controlled in its action from said traveling element in all positions of the latter.

9. The combination with a type action, of a key for operating said type action, a lock for said key, a computing mechanism having a traveling element, a bar connected to said lock so as to manipulate the same, said bar extending in juxtaposition to said traveling element for the full length of travel thereof, said computing mechanism having a series of computing wheels, and a bell crank lever universal to all of said computing wheels and engaging said bar in any position of said traveling element, whereby the position of said lock may be controlled from said computing wheels.

10. The combination with computing mechanism having a traveling element for indicating numbers, of printing means, and a lock for said printing means operable from said traveling element in all traveling positions of the latter, and dependent upon the number-indicating position of said traveling element.

11. The combination with computing mechanism, of printing means, a key for controlling the action of said printing means, locking means for said key, said computing mechanism having a traveling number-indicating element, and controlling means for governing said locking means from said traveling element, depending upon the number-indicating position thereof.

12. The combination with a master wheel and a computing head or a set of computing wheels, of a carriage along which said set of computing wheels is adjustable, a bar extending along the run of said carriage, a clearance-type key upon the framework of the machine and controlled by said bar, and means for causing said wheels, at any position of said carriage and at any adjustment of said set of wheels along said carriage, to operate through said bar to render said key effective or ineffective.

13. The combination with a totalizer movable to different lateral positions and comprising a set of computing members, of a clearance type, and means for operating said clearance type; said operating means including a device under the control of said computing members in all lateral positions of the totalizer.

14. The combination with a set of computing members, of a special type, said set of computing members being bodily adjustable or movable relatively to said type, and means controlled by said computing members in the various positions to which they may be adjusted or moved relatively to said

type, for controlling the operation of said type.

15. The combination with a set of computing wheels, of a special type, said set of computing wheels being bodily adjustable or movable relatively to said type, a bar along which said set of computing wheels is adjustable or movable, and means co-operating with said wheels and said bar in all positions to which the set of wheels are adjusted therealong, for controlling the operation of said type.

16. The combination with a set of computing wheels, of a special type, said set of computing wheels being bodily adjustable or movable relatively to said type, a bar along which said set of computing wheels is adjustable or movable, and an interponent between said set of wheels and said bar, and adjustable with said set, and serving to transmit movement between said wheels and said bar to control the operation of said type.

17. The combination with a set of computing wheels, of a special type, said set of computing wheels being bodily adjustable or movable relatively to said type, a bar along which said set of computing wheels is adjustable or movable, and an interponent between said set of wheels and said bar, and adjustable with said set, and serving to transmit movement between said wheels and said bar to control the operation of said type; said interponent comprising a tumbler, and said wheels having notches in alignment when the wheels stand at zero, to receive said tumbler.

18. The combination with a set of computing wheels, of a special type, said set of computing wheels being bodily adjustable or movable relatively to said type, a bar along which said set of computing wheels is adjustable or movable, a lock for said type, said lock controlled by said bar, and means to enable the computing wheels to control the bar.

19. The combination with a set of computing wheels, of a special type, said set of computing wheels being bodily adjustable or movable relative to said type, a bar along which said set of computing wheels is adjustable or movable, a lock for said type, a releaser for said lock, and means to enable the computing wheels to cause said bar to operate said releaser when the wheels all stand at zero.

20. In a recording calculating machine, the combination of a totalizer, means for printing a characteristic mark, mechanism for locking said printing means, and means rendering said locking mechanism ineffective when said totalizer stands at zero.

21. In a recording calculating machine, the combination of a totalizer, a key for printing a characteristic mark, mechanism

for locking said key, and means for rendering said locking mechanism ineffective when said totalizer stands at zero.

22. In a recording calculating machine, 5 the combination of a totalizer, actuating mechanism therefor, said actuating mechanism being adapted to insert numbers in said totalizer digit by digit, means for printing a characteristic mark, mechanism 10 for locking said printing means when said totalizer is in a predetermined position in relation to said actuating mechanism, and means rendering said locking means ineffective when said totalizer stands at zero.
- 15 23. In a combined typewriting and computing machine, the combination with computing wheels, and a platen, of a special type effective to print on said platen, means associated with said computing wheels for 20 holding said special type inoperative unless all said wheels stand at zero, and a key for operating said special type.

24. In a combined typewriting and computing machine, the combination with keys 25 and a traveling carriage, of type-actions actuated by said keys, certain of said type actions enabling a typewriting operation, one of said type-actions being adapted to print a distinguishing sign, a computing mechanism 30 including wheels, said computing mechanism being controlled by some of said keys, means for locking said sign-printing type-action, while leaving said other type-actions free to operate, and 35 means for rendering said locking means ineffective in certain predetermined positions of said wheels.

25. In a combined typewriting and computing machine, the combination with a 40 series of keys, certain of which are numeral keys, of a series of types, one type for each key, computing wheels, a master member

for turning said wheels, a traveling carriage in which said wheels are carried to engage said master member *seriatim*, a 45 clearance indicating type operable by one of said keys, a locking device, and a controlling member traveling with said carriage and under control of said computing wheels for enabling said locking device to 50 lock said clearance type against operation under predetermined circumstances.

26. The combination with keys and a traveling carriage, of type actions actuated by said keys to enable a typewriting operation, one of said type actions being adapted to print a distinguishing sign, a computing mechanism moving with said traveling carriage, a master member under the control of certain of said keys for engaging the 60 computing wheels in said computing mechanism *seriatim*, a rocking element traveling with said traveling carriage and under the control of said computing wheels, and means for locking said sign-printing type 65 action under the control of said rocking element.

27. In a combined typewriting and computing machine, the combination with a platen and devices for printing thereon, of 70 computing wheels, a single special key-operated type also printing on said platen, a rock arm associated with said computing wheels, a member associated with each computing wheel for holding said rock arm in 75 effective position, a locking arm for preventing operation of said special type, and a connection between said rock arm and said locking arm.
